Primary Examiner — Prabhakar Deshmukh(74) *Attorney, Agent, or Firm* — Nixon & Vanderhye P.C.(57) **CLAIM**

The ornamental design for a speaker panel for a jukebox, as shown and described.

DESCRIPTION

FIG. 1 is a perspective view of a speaker panel for jukebox showing our new design;

FIG. 2 is a front elevational view thereof; and,

FIG. 3 is a right side elevational view thereof, the left side elevational view being a mirror image thereof.

The dashed lines shown in FIGS. 1–3 represent environmental structure and form no part of the claimed design. Some views of the jukebox portions are not shown and represent unclaimed subject matter.
